UNITED STATES PATENT OFFICE

2,095,555

ADJUSTABLE NECKTIE AND STRIP APPLI-
CABLE THERETO

William Mayer, New York, N. Y.

Application September 23, 1935, Serial No. 41,670

2 Claims. (Cl. 2—155)

My present invention relates generally to neckwear, and has particular reference to an improved type of adjustable neckband.

It is a general object of my invention to provide an improved adjustable necktie of the general character illustrated in United States Letters Patent No. 2,003,359, issued June 4, 1935. This type of necktie has a neckband portion which is adjustable in length by doubling it back upon itself and by providing at its end a fastening element, such as a button or a hook, which is adapted to engage with a selected one of a series of openings or perforations in the neckband.

It is from some aspects undesirable to provide the perforations directly in the tie material, and for this reason it is preferable to provide an added separate strip of fabric in which the perforations are provided. The use of an extra strip is of particular advantage in permitting neckband sizes to be printed or embroidered thereon, and it usually affords a convenient means for applying a trade-mark or the like to the tie. However, the use of perforations with which a fastening element is intended to cooperate necessitates the provision of sufficient reinforcement to avoid the possible damage which a fastening element, such as a hook, might cause.

In accordance with my present invention, I have made unique advantageous use of a lining which is coextensive in length with the necktie, for the purpose of providing a device of the foregoing character.

Briefly, the present invention is characterized by the provision of a necktie element which consists of inner and outer plies of tie material, the inner ply being shorter in length than the outer ply to permit the added perforated strip of material to be attached to the rear of the inner ply and thereby form a continuation of the latter. This combination and arrangement of parts is coupled with the provision of a full-length lining, the rearward portion of which serves the function of a reinforcement for the perforated strip. More particularly, the rearward portion of the lining is provided with a series of longitudinally spaced perforations arranged in registry with the perforations in the continuation strip, and means are provided for marginally interengaging each pair of registering perforations.

In a preferred embodiment, the full-length lining is made of an integral piece of material. In a modified form of the invention, the lining is composed of two separate parts, a forward portion and a rearward portion, which are prefer-

ably, but not necessarily, fastened together at their contiguous ends.

A further modification provides for the reduction in width of the rearward portion of the lining, i. e., the portion which is perforated.

From one aspect, the invention relates to the separate assembly of perforated strip and lining, which, as a distinct article of manufacture, may be employed by manufacturers of adjustable neckties in the production of articles of the present novel character.

I achieve the foregoing objects, and such other objects as may hereinafter appear or be pointed out, in the manner illustratively exemplified in the accompanying drawing, wherein—

Figure 1 is a perspective view of a bow tie embodying the features of the present invention;

Figure 2 is an enlarged fragmentary longitudinal sectional view taken substantially along the line 2—2 of Figure 1;

Figure 3 is an enlarged cross-sectional view taken substantially along the line 3—3 of Figure 1;

Figure 4 is a perspective view of the added perforated strip assembly by itself, forming part 25 of a modified construction;

Figure 5 is a view similar to Figure 2, employing the assembly of Figure 4;

Figure 6 is a fragmentary perspective view, partly in section, and partly broken away, illustrating a further modification; and

Figure 7 is a perspective view showing the manner in which the present invention may be applied to a tie of the ready-made variety.

While I have illustrated my invention in association with a necktie of the bow knot variety, nevertheless it will be understood that the accompanying drawing is merely illustrative and that the tie of Figure 1 might just as well be a four-in-hand type of tie, and the tie of Figure 7 might just as well be a ready-made four-in-hand type of tie.

The construction illustrated in Figure 1 includes the knot-forming portions 10 and 11, the same having rearwardly extending neckband portions 12 and 13, respectively. The neckband of the tie is made adjustable in length by providing a male fastening element 14 (which I have illustratively shown in the form of a hook) at the extremity of the neckband portion 12, whereby this portion may be doubled back upon itself to engage the hook in any one of a series of longitudinally spaced perforations provided in a predetermined arrangement. A metallic loop 15 is mounted on the neckband portion 13 and the

neckband portion 12 extends through this loop.

The manner of applying the members 14 and 15 to the extremities of the neckband portions has not been illustrated in detail, because these 5 particular portions of the structure have no bearing upon the present invention. In fact, the present invention concerns itself only with the construction and arrangement of the element 12, and Figures 2-6 relate solely to this element.

10 The neckband element 12 is composed of the inner and outer plies of tie fabrics 16 and 17. These plies are usually of ornamental material, and in many instances they are of relatively delicate texture. The longitudinal edge portions of 15 these plies are turned inwardly and stitched together by concealed stitching, in a manner well known to those conversant with the art. This requires that the plies 16 and 17 be first assembled back-to-back and then, after stitching them together, the entire assembly is turned inside-out.

15 In accordance with my present invention, the inner ply 16 is not coextensive in length with the outer ply 17. More particularly, the outer ply 17 is of full length, and by this term I mean to 20 signify that it extends all the way from the knot-forming portion to the rear end at which the hook 14 is fastened; whereas the inner ply 16 extends only about half-way toward the rear end, the rear extremity being approximately at the 25 line 18 shown most clearly in Figure 1. The term "partial-length inner ply", as used herein and in the appended claims, is intended to allude to the foregoing general relationship between the 30 lengths of the plies 16 and 17.

35 At the rear end of the inner ply 16, it is associated with the forward end of an additional strip of fabric 19 which is coextensive in width with the plies 16 and 17 and which has its longitudinal edges turned in and secured to the outer 40 ply by the invisible stitches 20, as shown most clearly in Figure 3. The strip 19 is provided with a series of longitudinally spaced perforations which are designated generally by the reference numeral 21. Preferably, adjacent to the perforations, the strip bears indicia or markings 22 signifying neckband sizes.

45 My present novel construction includes, as an element thereof, the full-length lining 23, the term "full length" being intended to signify the fact that the lining is coextensive in length with the outer ply 17. The forward portion of the lining is coextensive in width with the tie, and has its longitudinal edges turned inwardly and engaged by the invisible stitches hereinbefore mentioned. In the embodiments illustrated in Figures 1-5, the rearward portion of the lining 23 is also of this width, as will be observed upon viewing Figure 3.

55 The rearward portion of the lining 23 is provided with a series of perforations registering with those in the strip 19, and means are provided for marginally interengaging each pair of registering perforations. I have illustratively shown buttonhole stitching 24 which accomplishes this purpose, but, obviously, metallic or other eyelets may be used, or the inter-engagement may be effected by any other suitable means.

60 In using the tie of Figures 1-3, it is obvious that the hook 14 may be engaged with any selected perforation and that this will adjust and vary the effective neckband length. Where a hook is employed, there is no danger of injury to the tie, because the strip 19 is adequately reinforced by the rearward portion of the lining 23. Even 65 where the fastener is in the nature of a button,

and the perforations in the form of buttonholes, this extra reinforcement is of advantage.

70 In Figures 4 and 5, I have illustrated a modified construction in which the strip 19 and the inner and outer plies 16 and 17 are exactly the 5 same in structural nature and mode of assembly as in Figures 1-3. The lining, in this case, is, however, not a single and integral element, but is composed of the two parts 25 and 26. The forward portion 25 is separate from the rearward 10 perforated portion 26, and these parts may be connected, as at 27, or they may be left in overlapped relationship. Conjointly, however, they define a full-length lining.

15 The advantage of the construction of Figures 4 and 5 lies in the fact that the strip 19 and the rearward lining portion 26 may be separately manufactured and may subsequently be associated with a tie construction which comprises the plies 16 and 17 and the forward lining portion 20 25. With this objective in view, it is a specific feature of the present invention to make the lining portion 26 of different length from that of the strip 19, so as to avoid the joint 27 from coinciding with the joint at the line 18.

25 The separate strip and lining assembly is shown by itself in Figure 4; and at the left of this figure it will be observed that the lining portion 26 projects beyond the end of the strip 19.

30 By virtue of the fact that the rearward portion of the lining is secured to the strip 19 by the means which inter-engage the registering perforations, it is not absolutely essential that the rearward portion of the lining be coextensive in width with that of the strip 19 or the ply 17. 35 It may be feasible, therefore, under certain circumstances, to modify the construction as illustrated in Figure 6. In this figure, the reference numerals 16, 17, 19, and 21 are applied to the parts hereinbefore designated by these numbers. 40 The lining element is designated by the reference numeral 27', and it will be observed that the forward portion, i. e., the portion sandwiched between the plies 16 and 17, is coextensive in width with these plies and has its longitudinal 45 edges inter-engaged with the longitudinal edges of these plies; whereas the rearward portion, i. e., the portion which is perforated and secured to the strip 19, is of reduced width with the longitudinal edges 28 entirely free. The advantage 50 of this construction lies in the reduced thickness of the longitudinal edge portions of the tie along the perforated region, this reduction in bulkiness facilitating the adjustment of this portion of the tie through the metallic loop 15.

55 Obviously, the modification of Figure 6 may be adapted to the structure of Figures 1-3; or it may be adapted with equal facility to the construction of Figures 4 and 5.

60 In Figure 7, I have illustrated the manner in which the invention is applicable to a tie of the ready-made variety. In this construction, the preformed knot 29 fulfills the function of the knot-forming portions 10 and 11 hereinbefore mentioned; and the rearwardly extending neckband portions 30 and 31 correspond to the portions 12 and 13 hereinbefore mentioned. The only difference in construction lies in the fact that a loop 32 is loosely mounted on the portion 30, and a hook 33 is adapted to engage therewith 65 when the tie is worn. In other respects, especially in connection with the adjustability of neckband length, the construction and mode of operation is the same as described hereinbefore. The element 30, from its forward end all the way 70 75

to its rear end, at which the hook 34 is applied, is the element to which the present invention has specific reference.

In general, it will be understood that changes 5 in the details, herein described and illustrated for the purpose of explaining the nature of my invention, may be made by those skilled in the art without departing from the spirit and scope of the invention as expressed in the appended 10 claims. It is, therefore, intended that these details be interpreted as illustrative, and not in a limiting sense.

Having thus described my invention, and illustrated its use, what I claim as new and desire 15 to secure by Letters Patent is—

1. In an adjustable necktie, an element whose forward end defines a knot-forming portion and whose rearward end is adapted to be doubled back upon itself, a fastener on the rear end of said 20 element, said element comprising a full-length outer ply and a partial-length inner ply of tie material, an added strip coextensive in width with the inner ply and forming a rearward continuation thereof, said strip having a series of 25 longitudinally spaced perforations into any one of which said fastener may be engaged, a full-length lining having in its rearward portion a series of perforations registering with those in said strip, and means marginally interengaging 30 each pair of registering perforations, the forward portion of said lining being coextensive in width

with said outer and inner plies and having its longitudinal edges stitched to the longitudinal edges of said plies, the rearward portion of said lining being of reduced width with its longitudinal edges free.

2. In an adjustable necktie, an element whose forward end defines a knot-forming portion and whose rearward end is adapted to be doubled back upon itself, a fastener on the rear end of said element, said element comprising a full-length 10 outer ply and a partial-length inner ply of tie material, an added strip coextensive in width with the inner ply and forming a rearward continuation thereof, said strip having a series of longitudinally spaced perforations into any one of 15 which said fastener may be engaged, a full-length lining consisting of separate forward and rearward portions, the rearward portion having a series of perforations registering with those in said strip, and means marginally interengaging 20 each pair of registering perforations, the forward portion of said lining being coextensive in width with said outer and inner plies and having its longitudinal edges stitched to the longitudinal 25 edges of said plies, the rearward portion of said lining being of reduced width with its longitudinal edges free, the forward end of said rearward portion being out of alignment with the forward end of said perforated strip.

30 WILLIAM MAYER.
